UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

TOY RACE-COURSE DEVICE.

Application filed December 7, 1925. Serial No. 73,655.

To all whom it may concern:

Be it known that I, FRED L. MILLS, a citizen of the United States, residing at Oak Park, in the county of Cook and State of Illinois, have invented a new and useful Improvement in Toy Race-Course Devices, of which the following is a specification.

This invention relates particularly to means for readily changing the permutation 10 in a toy race course of the character described in my Patent No. 1,559,120, issued Oct. 27, 1925.

The invention pertains particularly to the permutation-belt employed in a race course 15 of the character described in the above-mentioned patent, and in the combinations hereinafter set forth. The invention is illustrated in the accompanying drawing, in which—

20 Fig. 1 represents a broken elevational view of a toy race course constructed in accordance with the invention; Fig. 2, a broken plan view of the permutation-belt and a racer-positioning belt employed; Fig. 3, a broken plan view on a greatly enlarged scale, showing a fragment of the permutation-belt equipped with my improved catch device which serves as a racer-actuating member; and Fig. 4, a broken elevational view 25 of the parts shown in Fig. 3, the dotted lines showing the catch-member thrown to an inoperative position.

The drawing illustrates a toy race course 30 of the general construction and mode of operation set forth in the above-mentioned application. To enable the present invention to be understood, it is unnecessary to fully illustrate the apparatus described in said patent.

40 In the drawing, A designates a series of endless race tracks disposed in parallel vertical planes, the front one of said tracks being shown brokenly in Fig. 1; B designates a permutation-belt mounted on shafts 1 and 2; C designates a racer-positioning belt mounted on shafts 3 and 4; D designates a series of racers mounted on the parallel race tracks; and E designates a portion of a suitable cabinet containing the apparatus, the front side of the cabinet being provided with a view-opening, or window E'.

45 The shaft 2 is actuated in any suitable manner, preferably by means of an electric motor which is suitably controlled and 50 which will serve to move the racers through

the circuit and then come to a stop, if desired. The shaft 2 is connected by means of a belt 5 with the shaft 4, and thus serves to drive the racer-positioning belt C. A magnet-controlled clutch 6 controls the operation of the belt 5. The clutch 6 may, in turn, be controlled by an electric circuit, which electric circuit may be controlled by means of a note-producing device of a musical instrument. Such a device is described in the patent mentioned above. The cabinet E may comprise the cabinet of the musical instrument which controls the operation of the clutch 6.

55 The permutation-belt B is provided with several series of catches, or racer-actuating devices, B'. The devices B' may be of the construction illustrated in Figs. 3 and 4.

The racer-positioning belt C is equipped with a cross-member 7 which is adapted to engage the catch devices with which the racers are equipped. This action occurs after the racers have passed beyond the field of vision indicated by the window E', at which time the racers are also beyond the range of action of the permutation-belt. The racer-positioning belt serves to engage the racers and return them to the initial end 60 of the course, which appears at the right hand portion of Fig. 1.

65 A portion of an electric circuit is shown in Fig. 1 and is designated 8. It is, however, unnecessary to fully illustrate and describe the electric circuits employed. Each of the racers D is provided with a depending catch-member 9 which is adapted to be engaged by one of the catch-members, or racer-actuating members, B'. The members 9 may be of any suitable construction. They may be, for example, of the construction described in the 70 above-mentioned patent.

75 The catch-members 9 with which the racers are equipped are adapted to be engaged also by the member 7 of the racer-positioning belt C after the racers have passed beyond the range of action of the permutation-belt. The racer-positioning belt then serves to return the racers to the initial end of the course and bring them again within the range of action of the permutation-belt. It will be noted that the upper and lower reaches of the endless tracks A are joined by semi-circular end-portions 10.

80 The purpose of the improved racer-actuat-

ing members B' with which the permutation-belt is equipped is to enable any selected ones of said members to be thrown out of action at will. Each member B' comprises, 5 preferably, a mounting plate 11 secured to the permutation-belt by means of a rivet 11^a and provided with a longitudinal slot 11^b; a leaf-spring 12 secured to one end of the plate 11 by means of a rivet 12^a, the free 10 end of the spring projecting over the slot 11^b; and a small bell-crank lever 13 having a long arm 13^a, having a spring-actuated short arm 13^b at an angle to the arm 13^a, and having stop arms 13^c adapted to bear on 15 the plate 11.

The elbow portion of the lever 13 is provided at the edges with integral pivots 13^d which engage bearing recesses of lugs 11^e which are bent upwardly from the lateral 20 edges of the plate 11. The bearings 11^e are hook-shaped bearings, the points of the hooks being spaced a sufficient distance above the plate 11 to enable the pivots of the bell-crank lever to be entered in their 25 bearings. This may be done while the bell-crank lever is lying in the horizontal position, the spring 12 being readily depressed to permit the assembly of the parts.

The racer-actuators B' are so secured to 30 the permutation-belt that the levers 13 may be thrown forwardly to a folded position when it is desired to render the actuators inoperative. The lever cannot swing in a reverse direction beyond a vertical position 35 owing to the stops 13^c engaging the mounting plate 11.

The operation of the apparatus is the same as that described in the above-mentioned patent, and may be stated briefly 40 here. The racers may be assumed to start from about the position shown in Fig. 1 and to return to about the same position in a cycle of operations, it being understood, however, that the sequence of the racers may 45 vary, owing to the operation of the apparatus. The permutation-belt, in the illustration given, travels more rapidly than the racer-positioning belt. As indicated, the operation of a suitable motor for driving 50 the apparatus may be controlled by means of a coin, if desired. In the operation, the racer-actuators engage the depending projections 9 of the racers and move the racers along the upper reach of the race tracks until the racers are carried beyond the range of 55 action of the permutation-belt. The racers are then left in transverse alignment at the final end of the permutation-belt and presently are engaged by the member 7 of the racer-positioning belt C. The member 7 engages the catches 9 of all the racers, and returns the racers to the initial end of the race course and brings them within the range of action of the permutation-belt.

It will be noted from Fig. 2 that the racer-

actuators B' mounted on the permutation-belt occupy a staggered relation. By reason of the difference in the speeds of the two belts, a change in the sequence of the racers will occur when the racers are 70 brought again within the range of action of the permutation-belt at the initial end thereof. Also, as explained in the above-mentioned application, means may be provided for automatically changing the relative 75 movements of the two belts at regular or irregular intervals. For example, said patent describes means whereby the clutch 6, shown in the accompanying drawing, may be released when a certain note of the musical instrument is struck, thus permitting the racer-positioning belt C to stop momentarily, so that the relative movements of the two belts are thus varied. This results in a still further variation of the sequence of 80 the racers.

In accordance with the present invention, the racer-actuators B', carried by the permutation-belt, are foldably mounted on the belt and may be thrown into use, or out of use, 90 at will. When an actuator is folded to the position shown in dotted lines in Fig. 4, it will pass under the depending projection 9 of the racer and will fail to engage it. Thus, any actuator may be thrown out of use 95 readily when desired. The result is to vary the spacing of the effective racer-actuators, that is, of the actuators which are in operative position at any time.

It may be added that the plane of the 100 shafts 3 and 4 is below the plane of the shafts 1 and 2, so that while the racers are being returned to the initial end of the course, the racer-actuators B' will not engage the racers. Also, it may be pointed out that each mounting plate is preferably secured to the belt B at one point only, so that it will 105 not interfere with the flexibility of the belt when the belt passes about the pulleys.

The foregoing detailed description has 110 been given for clearness of understanding only and no unnecessary limitations should be understood therefrom, but the appended claims should be construed as broadly as permissible in view of the prior art.

What I regard as new, and desire to secure by Letters Patent, is:

1. In a device of the character set forth, a series of independently movable racers, and a permutation-belt equipped with 120 variable racer-actuators, whereby the sequence of the racers may be readily varied.

2. In a device of the character set forth, a series of independently movable racers, a permutation-belt, and racer-actuators carried by said permutation-belt adapted to be 125 thrown into operative or inoperative positions at will.

3. In a device of the character set forth, a series of independently movable racers, a 130

permutation-belt, and folding racer-actuators mounted on said permutation-belt and adapted to be thrown into inoperative position at will.

5. In a device of the character set forth, a series of parallel endless race tracks disposed in parallel relation, independently movable racers mounted on said tracks and provided with depending projections, a permutation-belt located between the upper and lower reaches of said tracks and equipped with variable racer-actuators whereby the sequence of the racers may be readily varied, and a racer-positioning belt equipped with 10 means for engaging the projections of said racers and returning said racers to the initial end of the course.

5. In a device of the character set forth, a series of vertical plane endless race tracks 20 disposed in parallel relation, independently movable racers mounted on said tracks and provided with depending projections, a permutation-belt interposed between the upper and lower reaches of said tracks, foldable 25 racer-actuators mounted on said permutation-belt, and means for engaging the racers

after they have passed the range of action of said permutation-belt and returning them to the initial end of the course and within the range of action of the initial end of the 30 permutation-belt.

6. A permutation-belt for the purpose set forth, equipped with a plurality of foldably mounted racer-actuators.

7. A racer-actuator for the purpose set 35 forth comprising a mounting plate equipped with a spring, and a foldably mounted bell-crank lever having a tongue engaging said spring and having a stop adapted to engage said mounting plate, whereby said lever may 40 be folded on the plate in one direction only.

8. A racer-actuating device for the purpose set forth comprising a mounting plate having its lateral edges equipped with hook-shaped lugs affording bearings, a spring 45 mounted on said plate, and a bell-crank lever having pivots removably engaging said bearings, having a tongue engaging said spring, and having a stop engaging said plate.

FRED L. MILLS.
